VENTILATING SYSTEM FOR STOCK BUILDINGS

Original Filed Sept. 27, 1926

Inventor
August Zacharias
By his Attorney
Merchant and Negus

UNITED STATES PATENT OFFICE.

AUGUST ZACHARIAS, OF MINNEAPOLIS, MINNESOTA.

VENTILATING SYSTEM FOR STOCK BUILDINGS.

Original application filed September 27, 1926, Serial No. 137,944. Divided and this application filed November 18, 1927. Serial No. 234,121.

My present invention relates to a ventilating system for stock buildings and is a division of my co-pending application filed September 27, 1926 under Serial Number 137,944, 5 which has matured into Patent Number 1,670,872, dated May 22, 1928.

In the accompanying drawings, which illustrate the invention, like characters indicate like parts throughout the several views.

10 Referring to the drawings:

Fig. 1 is a fragmentary view principally in horizontal section showing the invention installed in a chicken coop;

15 Fig. 2 is a view principally in vertical section taken on the irregular line 2—2 of Fig. 1; and

Fig. 3 is a view of the ventilating stack partly in longitudinal central section and partly in elevation.

20 The numeral 6 indicates a building divided into chicken coops 7, only one of which is shown in full. The ventilation of each coop 7 is independent of the other and each system includes a stack 8, located in the center 25 of the coop 7, and, as shown, four fresh air intake boxes 9, located, one in each corner of said coop. The lower end of the stack 8 is open and supported just above the floor of the coop 7 on legs 10. Said stack 8 extends through the roof of the coop 7 to a 30 considerable distance thereabove in order to produce the necessary draft to draw the foul and damp air out of said coop.

The lower or intake end portion of the 35 stack 8 has a much larger air conducting capacity than the balance of the stack 8, so that the foul and damp air is slowly taken into said stack without creating any noticeable draft. A cap 11 is attached to the 40 stack 8 and supported above the discharge end thereof to prevent rain and snow from entering said stack and also to prevent wind from blowing down into the stack 8.

Formed in the stack 8 just under the roof 45 of the coop 7 is a short lateral hot air intake pipe 12 having a displaceable closure cap 13. A damper 14 is mounted in the stack 8 below the hot air intake pipe 12.

Each fresh air intake box 9, as shown, is 50 secured to the inside wall of the coop 7 and is provided with a fresh air intake pipe 15 and two fresh air discharge pipes 16, located above said intake pipe. The air intake pipe 15 extends outward through the wall of the coop 7 and has a down turned receiving end to

prevent rain or snow from entering the same. A damper 17 is mounted in intake pipe 15, and a damper 18 is mounted in each discharge pipe 16.

The two discharge pipes 16, which open directly into the coop 7, are laterally spaced, the one from the other, and have substantially the same air conducting capacity as the intake pipe 15. Mounted in each air intake box 9 is a plurality of staggered baffle plates 19, 60 arranged to cause the air passing through said box into the coop, same to travel a zigzag course. The air capacity of each box 9 is relatively large in respect to the intake pipe 15. Obviously, the damper 17 is operable 65 from the outside of the building 6 and the dampers 18 are operable from the inside of the coop 7.

The stack 8 is also provided with a short radial pipe extension 20 having a slide damper 70 75 21 and to which extension may be attached an exhaust fan, not shown. Said extension is located substantially diametrically opposite the hot air intake opening 12. The use of an exhaust fan for the stack 8 would preferably be used only when the building is provided with a cupola.

When a building in which the ventilating system is installed has double walls, the fresh air boxes 9 may be placed between said walls. 80 85 By the use of the damper 14, the discharge of the foul, damp air from the coop 7 may be controlled. The dampers 17 and 18 may be operated to control the supply of fresh air taken into the coop 7. In summer time the cap 13 90 95 may be removed to draw off the hot air at the top of the coop 7 to lower the temperature in said coop.

The ventilating system is designed to keep the coop 7 supplied with an abundance of 95 fresh air and remove the foul, damp air therefrom without creating any draft in the coop 7. The baffle plates 19 will cause the fresh air to travel slowly through the boxes 9 and quietly enter the coop 7.

By the use of the improved ventilating system the heat in the coop 7 is conserved, and as is well known, when a coop is properly heated and ventilated, less feed is required for the chickens and they are kept in better 100 105 health.

The arrangement of the stack 8 in the building, to wit: centrally located, and the fresh air intake box 9 is highly important in that there are no dead air spaces in the building. 110

By this arrangement of the ventilating device, fresh air is being continuously taken into the building throughout all parts thereof, and the foul air removed from the lower portion 5 of the room. This ventilating system not only supplies fresh air to all parts of the building, but it prevents dampness and keeps the floor in a dry condition.

What I claim is:

- 10 The combination with a building, of a straight continuous ventilating stack in the

building having a foul air intake opening close to the floor, the intake portion of the stack having a greater air-conducting capacity than the discharge portion thereof, said 15 stack having a hot air intake opening close to the roof, a damper in the stack below said intake opening, and a displaceable closure for the intake opening.

In testimony whereof I affix my signature.

AUGUST ZACHARIAS.
